Application March 22, 1934, Serial No. 716,894
Renewed March 22, 1938

3 Claims. (Cl. 244—37)

This invention relates to improvements in airplanes, and more particularly to improved flaps and combinations of airfoils and flaps.

The advantages of a high lift coefficient during landing and takeoffs, coupled with a reduced coefficient during normal flight, have long been appreciated by airplane designers. Many suggestions have been advanced as to the best methods of attaining these results. Of the many proposals there are two which have achieved not an inconsiderable success in actual operation. These are the slotted wing and the flap.

The flap, so called, in its broadest aspect is in effect a device which changes the effective curvature of the wing. When the flap is operated by being opened downwardly of the wing, the result is that the wing surfaces are made more concave, giving in effect a high cambered wing, and resulting in an increase in lift. This is true whether a leading edge or a trailing edge flap is considered. The change in curvature is of course greatly accentuated if both a leading and a trailing edge flap are mounted on the one wing.

Upon operation of a flap, a concomitant of the increased lift is an increased drag. This, however, is a real advantage, for the increase in drag permits a steeper gliding angle at lower landing speeds.

While the utilization of a flap does present some advantages, they are not without inherent disadvantages. The employment of this extra mechanism naturally adds weight to the plane. It has been found also that when the flaps are moved to the operative position the airplane is more difficult to control. A major reason for this is that as the flap is depressed, the center of pressure on the wing is displaced. This of course is a decided disadvantage, inasmuch as it changes or modifies the balance of the airplane. Another drawback of such flaps is that upon operation the air flow in the rear of the trailing edge of the wing is disturbed or rendered more turbulent, and this considerably reduces the effectiveness of the empennage surfaces and particularly the stabilizer.

It is an object of the present invention to improve the operation of an airplane by utilizing the split flap principle and correlating this with other factors of design.

Another object is to provide an airplane in which flaps are associated in a novel manner with control surfaces.

Another object is to provide a novel type of wing cellule utilizing a split flap.

With these and other equally important objects in view, the invention comprehends the several

combinations shown in the drawings and to be described in the specification; it being understood that these combinations are given as illustrative of the principle involved rather than as restrictive definitions of given mechanism.

In order to more clearly explain the invention, physical embodiments are shown in the accompanying drawings, in which:

Figure 1 is a top plan view of one type of plane embodying the principles of the present invention.

Figure 2 is a front elevation of the plane shown in Figure 1.

Figure 3 is an enlarged detail taken on line 3—3 of Figure 2.

Figure 4 is a top plan section of an improved wing cellule.

Figure 5 is an elevation of the portion of the structure shown in Figure 4.

Figure 6 is an enlarged cross sectional detail taken on line 6—6 of Figure 5.

Figure 7 is a plan view of yet another modification of the invention, utilizing the flap and an improved type of aileron.

Figure 8 is a front elevation of the device shown in Figure 7.

Figure 9 is an enlarged cross sectional detail taken on line 8—8 of Figure 8.

Figure 10 is a top plan view of yet another type of wing cellule embodying the present invention.

Figure 11 is a front elevation of the part shown in Figure 10.

Figure 12 is an enlarged cross section taken on line 12—12 of Figure 11.

Figure 13 is a plan view of a wing cellule somewhat similar to that shown in Figure 10.

Fig. 14 is a front elevation of the part shown in Fig. 13.

Fig. 15 is an enlarged cross section taken on line 15—15 of Fig. 14.

Fig. 16 is a plan view of yet another modification of the invention.

The fundamental concept of the present invention is to obtain the advantages of flap operation, while using a simple form of split flap, and yet obtain optimum effect from the control surfaces such as the ailerons. Within the spirit of the present invention are comprehended a number of different specific arrangements or combinations whereby this result may be secured, namely the retention of full effectiveness of aileron surfaces while nevertheless securing the full advantages of flap operation.

It is known to those skilled in the art that one of the disadvantages of the incorporation of flaps upon airplanes has been the undesirable effect

upon control surfaces, rendering these as a general rule, less effective than before the installation of the flap. According to the principles of the present invention, the full advantages of the two devices may be secured.

The invention also comprehends the provision of novel types of control surfaces which are specifically designed not only in respect of the structure but also their operation to counterbalance or nullify the disadvantages of the flap. This principle will be more readily comprehended upon a consideration of several mechanical structures in which these advantageous results are secured. As shown in Figures 1, 2 and 3, the advantages of split flap operation may be secured without any drastic modifications of the main sustenation surfaces by utilizing a new type of control surface and by properly positioning this with respect to the location of the flap. In order to clarify and simplify the description, there are shown in the drawing only those portions of an airplane which are essential to an understanding of the invention. In all of the figures, merely a portion of the fuselage and the wing surfaces are shown. It will be understood, however, that these figures are intended to illustrate a completely operative machine. The conventional elements such as power plant, propeller, and empennage structure are well known to those skilled in the art, and are contemplated here.

As shown in Figure 1, an airplane made in accordance with the present invention may comprise a fuselage 1 provided with the essential appendages, not shown. Suitably secured to the fuselage are the main wings 2. Preferably these are secured at an upper portion of the fuselage. Secured to a lower portion of the fuselage and extending upwardly at a decided positive dihedral angle are the strut wings 3 and 4. Preferably these terminate short of the underside of the wings and are attached to the wings by suitable tension means 5 and bracing means 6. The front strut wing 3 is of airfoil form and is provided with suitable structural elements such as spars and ribs, whereby its functions as a strut and also as an airfoil are subserved. The lift strut 4 may be of the same general design as the lift strut 3, but differs from it in being mounted for rotation about the axis 7. The main wing is constructed without ailerons, but is provided with the flap 8. This flap may be of any form; it is shown as a split flap, pivoted for rotation on the pivot 9. Suitable transmission mechanism extends from the flap 8 to the cockpit, by reason of which the flap is operated. As shown in Figure 1, the flap may extend the full span of the wing. If desired of course the flap may be terminated short of the wing span, and instead of being rectilinear, as shown, may be of any desired configuration. It is to be observed that the main wing 2 is not provided with the usual type of aileron. Control is secured by utilizing the lift struts 4 as ailerons. By rotating these about their axes on one side or the other of the plane, it will immediately be appreciated that a rolling moment may be given to the airplane.

It will be appreciated in these circumstances that the member 4 subserves a number of functions. In the first place, in normal horizontal flight it acts as an air sustenation surface, adding materially to the lift of the plane. In an angle of bank, due to its dihedral setting, its horizontal equivalent increases and thus imposes an automatically increased lift on the low side. By rotating this member about its axis, its angle of

incidence may be varied and the effective lift thereby changed to serve as a control surface or aileron.

It will be appreciated that by utilizing such a member, the incorporation of the flap and the utilization of the flap principle becomes relatively simple. In a sense, the aileron 4 is considerably displaced from the flap and whatever the position of the flap a smooth uninterrupted flow of air over the aileron 4 obtains. If desired, it will be appreciated that each lift strut 3 and the lift strut 4 may be employed as control or aileron surfaces. The method of connecting these up for simultaneous operation to perform this function will immediately be perceived by those skilled in the art. If desired also the aileron 3 may be mounted for rotation and utilized not as an aileron but as a means for compensating for the shift in the center of pressure on the wing 2, due to the operation of the flap 8. As is known, when the flap 8 is depressed, the effective curvature of the wing is increased and an increased lift results. However, a concomitant of this increased lift and/or the change of the curvature is a shift in the center of pressure of the wing 2. This shift tends to unbalance the plane. In the present invention, however, this unbalance is compensated for and equilibrium attained by a correlation of factors including the effect of the downwash on the tail surfaces, due to the operation of the flaps, and the rotation of the supplemental wing 3 about its axis. It will be observed, therefore, that this type of plane provides for improved operation. The main wings 2 may be mounted high in the fuselage. While they are shown attached to an upper portion of the fuselage, it will of course be appreciated that they may be spaced above the fuselage and suitably secured to it through the medium of cabane struts. By positioning the main wing high on the fuselage or by spacing it above the fuselage, it will be appreciated that the depression of the trailing flap will increase the downwash on the tail surfaces thus imposing a force tending to compensate for the shift in the center of pressure on the main wing. With this is correlated the position and/or movement of the airfoils 3 and 4 which serve further to minimize the longitudinal unbalancing effect due to the operation of the flaps. By employing this relatively high position on the main sustenation surfaces and a relatively low position of the ailerons, the maximum control effect of the ailerons is secured whatever the position of the flap.

The major advantages above pointed out may be secured with other and specifically different structures. An example of such structure is shown in Figures 4, 5 and 6. In these figures, as in Figure 1, the structure includes the fuselage 1, with which are associated the necessary elements (not shown) such as landing gear, power plant and propeller, empennage units and so forth.

Similarly to the device shown in Figure 1, the airplane shown in Figure 4 is provided with the main wings 2, which are properly filleted at the fuselage as indicated at 2'. The wing is provided with the trailing edge flap 8 hinged to the underside of the main wing either on or adjacent the rear spar. The flap may extend any predetermined distance along the span of the wing; as shown, it extends the full span of the wing.

Associated with the fuselage and the main wing is the aileron wing 10. This preferably terminates short of the under surface of the main wing as at 11 and is securely attached to structural ele-

ments of the wing such as the spars, by the securing means 12 and 13. The wing may be of any desired span and chord, depending upon the characteristics of the particular plane on which it is to be mounted, and the control effect and/or the degree of maneuverability desired. The aileron wing 10 which is shown is of the long narrow type and is somewhat tapered. While this type is not as efficient as is the short aileron in producing a roll for a given angle of throw, nevertheless it is very effective for all practical purposes and has the advantage of requiring less effort on the part of the pilot, due to the smaller moments about the hinge pin. It will readily be appreciated that the effective area of the wing 10 may be modified by a designer to conform to his particular ideas as to the most effective wing-aileron area ratio.

The wing 10 is mounted for rotation on the axis 12, which is shown as approximately in the area of the center of pressure of the aileron wing.

The operation of this type of airplane is, in essentials, the same as that shown in Figure 1. The actuation of the flap 8 increases the lift on the wing 2. As pointed out hereinbefore, depression of the flap materially increases the downwash on the tail surfaces which thus compensates in some degree for the shift in the center of pressure on the main wing. Further compensation or nullification of this shift in pressure is secured due to the position and/or potential movement of the airfoil 10. Thus full effectiveness of the longitudinal control surfaces is secured. By rotating the strut wing 10 on one side of the plane to properly change its angle of incidence, a rolling moment may be imparted to the entire plane. It is to be observed also that the aileron wing 10 is located within the vertical plane including the shifting center of pressure of the main wing 2. This aileron wing therefore tends to minimize the tendency of an unbalanced condition due to the change in the center of pressure.

Another method of securing the full advantage of the flap while yet retaining the maximum effectiveness of the aileron surface is illustrated in the device shown in Figures 7, 8 and 9. In this device the main wing 2 is attached as described to the fuselage 1. This main wing is provided with a flap 8 extending any desired length of the span. Associated with the main wing is a stub wing section 15 and the positive dihedral section 16. The wing cellule may be additionally strengthened by utilizing inter-plane braces as indicated at 17. As shown in Figure 7, the wing section 16 is preferably tapered toward the tip and is secured to the underside of the main wing in a manner similar to or comparable with the attachment shown in Figures 1 and 4. In all of these structures the purpose of such an attachment is to diminish interference effects between the upper surface of the lift strut and the under surface of the main wing.

In the device shown in Figures 7, 8 and 9 the aileron surface is displaced from the main wing. In this particular case the aileron 18 is mounted at a position above the wing by means of the aileron braces 19. The aileron may be rotated by means of actuating mechanism extending to the cockpit. By positioning the aileron above the wing and the flap on the lower surface, it will be appreciated that operation of the flap does not materially affect the air flow over the aileron, and hence does not diminish its efficiency. Such a combination of flap and a displaced aileron is

made particularly effective in a plane of the type shown. The lift strut 16 is so designed, both with respect to size and attitude, as to compensate for the shift in the center of pressure on the main wing due to the operation of the flap. As described, this compensation is correlated with that resulting from the effect of the downwash on the tail surfaces due to the operation of flap 8. This combination, therefore, in effect comprises a wing cellule in which a flap is operative but in which an airfoil of appreciable surface is provided, the center of pressure of which is substantially unaffected by the operation of the flap on the main wing. It will thus be understood by those skilled in the art that the initial setting of the wing sections 15 and 16 may be made with respect to the shift in the center of pressure or the area of the center of pressure of the main wing, the area of the center as modified by the effect of the downwash due to the operation of the flap. This type of structure, therefore, largely minimizes one of the outstanding disadvantages of the flap, namely, its effect in unbalancing the plane due to the shift in the center of pressure on the wing associated with the flap. Similarly to the major concept involved in the design of the other modifications, the aileron surface is so positioned as to maintain its full effectiveness despite the position of the flap 8. As has been previously described, the lift strut 16 may be mounted for rotation along its chord and may be operated either manually or automatically to vary its angle of incidence simultaneously with the operation of the flap, so as to compensate for or nullify the unbalance effected by the operation of the flap.

Yet other types of apparatus may be constructed which include the novel principles of the present invention. An example of such a structure is shown in Figures 10, 11 and 12. As in the other devices, this structure includes a fuselage 1, a main upper wing 2, a stub wing 15 and a lift strut 16 connected at one end to the under side of the main wing and at the other to the stub wing section 15. If desired, the wing cellule may be rigidified by using the inter-plane bracing members 17. In this type of plane, as in the others, the aileron is displaced a sufficient distance from the flap to insure its efficient operation, regardless of the position of the flap. One method of accomplishing this, as shown particularly in Figure 12, is to mount the split flap 8 upon the under side of the main wing 2. The ailerons may be embodied in the stub wing or the lift strut or both. For purposes of illustration, it is shown only as associated with the lift strut. As shown in Figure 12, the aileron 20 is pivotally connected at the trailing edge of the strut airfoil 16. The aileron may be hinged to this strut in the usual manner and operated by conventional mechanism. Since the lift strut is of rather large area, it will readily be perceived that by mounting ailerons at the trailing portion of the lift strut, sufficient control area may be secured. It will be observed that this type of plane presents improved operation. When the plane is in normal horizontal flight in the air and the split flap 8 is closed, both the wing sections 2 and 16 contribute to the lift. The wing section 16, due to its dihedral setting, tends to render the plane automatically stable and materially checks sideslip. Lateral control or maneuverability of the plane is secured by operating the ailerons 20 in the usual manner. As

noted above, the rolling moment development by the aileron 20 on the lift strut 16 may be supplemented by ailerons mounted upon the stub wing 15. When the flap 8 is operated by being depressed, the effective lift of the upper wing 2 is increased. Any turbulence or disturbance of air flow caused by the flap 8 has no material effect upon the aileron 20, due to the rather wide spacing of displacement of these two.

10 It will be observed from the showing in Figures 10 and 12 that the aileron 20 extends to a position quite close to the underside of the main wing. It will be understood that this position may be varied within rather wide limits, depending upon 15 the desires of the designer. It will be observed that a device is shown in Figures 10 to 12 in which the aileron extends close to the upper wing and that when the aileron is in the up position the air flow is restricted and there is 20 thus produced a desirable yawing effect. It will also be observed that in this structure as in the others, the wing surface 16 may be so positioned with respect to the upper wing 2 as to largely 25 compensate for the shift in the center of pressure on the main wing 2. In other words, the wing setting of the wing section 16 may be established not only with regard to its effectiveness as a wing surface, but also its effect in stabilizing the airplane when the flap 8 is operated.

30 This effect can be made quite marked, particularly in view of the fact that the wing section 16 is largely within the vertical plane of the center of pressure of the main wing.

The fundamental advantages of an airplane 35 constructed as shown in Figures 10, 11 and 12 may be secured in another manner, such for example as is shown in Figures 13, 14, and 15. In these figures the airplane comprises the fuselage 1, main wing 2, stub wing 15 and lift strut 16. 40 The main wing may be considered a conventional wing formed with the conventional aileron 20 mounted, as shown, at the trailing edge of the main wing for an appreciable portion of its span. This aileron is operated by controls well known to those skilled in the art. The lift strut 16, and if desired the stub wing 15, are provided with the split flaps 21 and 22. These flaps may be of conventional form and are pivotally mounted upon a structural element of the airfoil surface. In this type of construction, it will immediately be perceived that the advantages of flap operation are secured while yet maintaining the full effect of aileron operation. The wing section 15 occupies a relatively low position on the fuselage and depression of the flap 22 below this wing surface does not materially affect the air flow over the stabilizer and elevator. The flap 21 on the wing section 16, while occupying a higher position, is nevertheless spaced quite a 50 distance laterally of the fuselage, hence burbling or turbulence caused by operation of the flap 21 does not affect the air flow over the empennage structure to any considerable extent.

While the flap 21 has been shown as of relatively small dimensions and being mounted on the rear spar of the wing element 16, it will readily be appreciated that it may be of any desired size and shape. It will be further understood that the flaps 21 and 22 on each side of the plane may be operated simultaneously or separately and successively. In the device shown in Figures 13, 14 and 15, the operation of the flap will of course cause a shift of the center of pressure above the wings 15 and 16. Since, 70 however, the center of pressure on the main wing

is not modified by the operation of the flap, the balance of the plane is not seriously affected.

While the structures shown in Figures 4, 7, 10 and 13 include a single lift strut, it will be understood that the principle of operation involved in these apparatus may be utilized on planes embodying two or more struts, such for example as is shown in Figure 1. In such cases, one or both of the lift struts may be mounted for rotation so as to jointly serve as ailerons or control surfaces, or, as described, one may be employed as an aileron and the other may be availed of as a means of automatically restoring the longitudinal balance of the plane due to the shift in the center of pressure on the wing on which the flap is mounted.

In the devices shown in Figures 1 to 15, inclusive, the split flap and ailerons are shown as being mounted on separate wing members or, as in the case of Figure 9 they are mounted on the same wing member and relatively widely spaced. It will be appreciated that the major advantages of the present invention may be secured with yet other structures such as one in which the split flap and the aileron are mounted on the same main wing. An example of such structure is shown in Figure 16. In the device shown in this figure, the airplane may include the fuselage 1, the upper main wing 2 and the lift strut 3.

The root section of the main wing is provided 30 with the split flap 23 suitably pivoted to a structural part of the wing, and the aileron 24 is mounted for pivotal movement at the outer or tip end of the wing.

It will be seen that the major factors of operation hereinbefore described apply in the present case. By properly positioning the lift strut 3 with respect to the normal center of pressure of the main wing and properly correlating its wing setting, it will be appreciated that material shifts in the center of pressure on the main wing, due to the operation of the flap, can be in a large measure compensated.

While in most of the figures of the drawings a high wing monoplane has been described, it will be understood that the principle described herein may be utilized with a low wing monoplane. In such circumstances, the main wing may be attached to a low part of the fuselage and strut wings 3 may be secured to the upper part of the fuselage and extend downwardly at 50 a negative dihedral angle to be attached by suitable means to the upper surface of the main low wing. In other words, in a sense, the position of the main and strut wing shown, for example, in Figures 1 and 5, may be inverted or reversed.

It will also be appreciated that in a combination of the character described, additional beneficial functions are obtainable. For example, the lift struts may be pivotally mounted at the fuselage and at or near their tip end, so as to be rotatable. The lift struts may be connected to control means within the cockpit and the mounting of the lift struts, and the associated control means may be so correlated as to utilize the lift struts as floating ailerons. In these circumstances, maximum aileron control is secured even at high or exaggerated angles of attack when the main wing approaches its position of minimum lift.

It will be understood that within the scope of the present invention any desired type of flap may be employed. The flap 8 shown in the several figures in the drawing comprises a member, nested in its inoperative position, within the con- 75

tour of the main wing and pivotal about a point on the main wing. This flap, however, may be spaced from the main wing and may be of a compound movement type. In short, any desired 5 type or character of flap may be employed herein.

It will be manifest that in all of the modifications shown the fundamental principle is the same, namely, the concept of securing full value 10 from flap operation while nevertheless utilizing 10 to the greatest possible degree the control surfaces. In some circumstances, as has been described, it is possible to aggregate with these advantages the further advantage of an optional or automatic restoration of longitudinal balance by 15 compensating for or nullifying the effect of the shift in the center of pressure on a wing carrying a flap.

Therefore, while specific embodiments of the invention have been described, it is to be understood 20 that these are given merely as illustrative of the principle involved; the specific structures shown are given merely to typify the embodiment of such principle and not as definitions of or limits upon the scope of the invention.

25 I claim:

1. An airplane comprising a main wing section on each side of the fuselage, a split flap pivotally mounted on each section; a plurality of airfoils mounted on each side of the fuselage and attached 30 respectively to the underside of the main wing and to the fuselage, means to change the attitude of one of said airfoils to impose a rolling moment on the airplane, and means to change

the attitude of the other said airfoil to compensate for changes in the center of pressure on the main wing due to the operation of the flap.

2. An airplane comprising a fuselage, a main wing attached to a high point of the fuselage at each side thereof, a plurality of rotatable lift struts on each side of the fuselage and attached respectively to the fuselage and main wings, a split flap pivotally mounted on the main wing, and means to independently rotate the lift struts 10 to vary the lifting effect of the struts so as to impose a predetermined rolling moment on the plane and to compensate for changes in the center of pressure of the main wing due to the operation of the flap.

3. An airplane comprising a fuselage, a main wing section attached to the upper portion of the fuselage at each side thereof, a plurality of substantially parallel independently rotatable strut wings on each side of the fuselage and attached respectively to a lower portion of the fuselage and to the underside of the main wing; a split flap pivotally connected to the main wing and being so positioned that downwash therefrom reacts upon the horizontal stabilizer of the plane, and 25 means to change the lifting effect of one of the strut wings to impose a rolling moment upon the plane and means independently to change the attitude of the other strut wing and compensate for changes in the center of pressure on the main 30 wing due to the operation of the flap.

GIUSEPPE M. BELLANCA.
